A. E. ROEVER,
VACUUM ASH SIFTER,
APPLICATION FILED MAY 27, 1920.

1,355,508.

Patented Oct. 12, 1920.

3 Inventor:
August E. Roever
By his Attorney
G. M. Reed

UNITED STATES PATENT OFFICE.

AUGUST E. ROEVER, OF BROOKLYN, NEW YORK.

VACUUM ASH-SIFTER.

1,355,508.

Specification of Letters Patent. Patented Oct. 12, 1920.

Application filed May 27, 1920. Serial No. 384,553.

To all whom it may concern:

Be it known that I, AUGUST E. ROEVER, a citizen of Germany, (who has applied for naturalization as a citizen of the United States, having received his first papers before war was declared by the United States against Germany, and who still expects to become such citizen of the United States,) residing at Brooklyn, in the county of Kings, city and State of New York, have invented certain new and useful Improvements in Vacuum Ash-Sifters, of which the following is a specification.

This invention relates to ash separators or sifters particularly adapted for use with motor driven vacuum cleaner apparatus, the object of the invention being to provide an improved separator or sifter for the purpose specified, very simple in construction and operation and durable in use and which can be readily used with an ordinary household or portable motor driven vacuum cleaner by merely placing the same on top of the separator or sifter.

In the drawings accompanying and forming a part of this specification, Figure 1 is a side view partly in vertical section of this improved vacuum sifter or separator, the dotted lines illustrating a portable motor driven vacuum cleaner placed on top of the cover of the sifter; Fig. 2 is a plan view partly broken away; and Figs. 3 and 4 are detail views of part of the cover.

Similar characters of reference indicate corresponding parts in the several figures of the drawings.

In the preferred form thereof, this improved separator or sifter comprises preferably a metal box of a suitable size adapted to be set upon an ordinary metal ash can. This box 2 is provided at one side with an inlet or nozzle 3 for the reception of a suitable conduit or hose leading to a suitable nozzle adapted to be used with ashes, such for instance as that shown and disclosed in my contemporaneously pending application filed simultaneously herewith. This inlet 3 opens into one compartment as the bottom compartment 4 of the receptacle or box, this compartment being divided from an upper compartment 5 by a suitable screen or separating medium 21 preferably of cloth or fabric through which the air may percolate and by means of which the dust and dirt are prevented from passing from the compartment 4 into the vacuum cleaner. The

bottom of the receptacle is provided with a depending chute 6 having a discharge outlet 6' of suitable size adapted to open into an ash can. The bottom of this outlet 6 is 60 provided with a closure or cover 7 hinged to the outlet 6' and of substantially the same size as said outlet, and provided with a suitable means for opening and closing it, and which opens downward for the discharge of 65 the dust and dirt.

In the present instance this means consists of a connecting rod or link 8 having its upper end connected to one arm as 9 of a rock shaft 10 suitably mounted in the side 70 wall of the receptacle 2, and on its outer end provided with a suitable handle 11. The movement of the handle in one direction is limited by a pin 12 and by throwing the handle against this pin 12 (see dotted line 75 position Fig. 1), the closure 7 is closed against the lower end of the outlet 6 and maintained in such closed position by reason of the fact that the connecting rod or link is thrown past its dead center position, 80 and thus locks the door shut against premature opening.

The receptacle is provided with a suitable preferably removable cover 13 maintained air-tight by means of a suitable packing 14 85 either carried by the cover or by the top edge of the receptacle. This cover is provided with an elongated slot 15 faced or inclosed by a suitable packing of felt 16 and with a pair of handles 17.

It will be understood of course that the various details may be more or less changed without departing from the spirit or scope of the present improvement.

In operation, the cover having been tightly 95 fitted to the box and the box 2 placed on top of an ash can 20 in the manner shown in Fig. 1, an ordinary portable electric vacuum cleaner 30 is placed on top of the receptacle cover with the inlet 31 of the vacuum cleaner 100 in juxtaposition to the slot or opening 15 of the cover, which is of substantially the same area as that of the cleaner. A suitable hose and nozzle are attached to the inlet 3 and the closure 7 closed whereupon on operating 105 the motor driven cleaner suction will cause the particles of dirt and dust of the ashes to be drawn in through the nozzle 3 into the receptacle 4 and the air purified and drawn through the screen 21, the slot 15 and into 110 and through the motor-driven cleaner. In this manner the cleaner is maintained free

from dirt and dust, which all settles and remains in the lower compartment 4 of the receptacle 2. When the same is filled or partially filled, the operator by manipulating 5 the handle 11 opens the outlet 6 and permits the same to drop into the ash can.

Thus the present improvement provides a very effective and sanitary ash separator or sifter, simple in construction and efficient in 10 use, and which as stated, can be used with an ordinary vacuum cleaner or portable motor driven vacuum cleaner, which may in practice be suitably clamped or secured to the cover or to the handles 17 thereof if 15 preferred to maintain it in place.

I claim as my invention:

1. A vacuum ash separator adapted to rest upon an ash can and comprising a receptacle having an inlet at one side, a discharge outlet at its underside, a separating medium dividing said receptacle into a pair of compartments, the upper compartment having a top adapted to receive and support a portable vacuum cleaner provided with a mouth, 20 and said top having a slot adapted to communicate with said mouth and swinging downwardly controlled closing means for said discharge outlet.

2. A vacuum ash separator comprising a 30 receptacle comprising a top and bottom compartment having therebetween a separating medium, an inlet into the lower compartment at one side thereof and a discharge outlet from the lower compartment at the bottom thereof, manually operative pivotal means for closing said outlet, and a cover for said upper compartment, said cover having a slot adapted to be located in juxtaposition to a vacuum cleaner.

40 3. The combination with a motor driven portable vacuum cleaner, of a vacuum ash separator adapted to rest upon an ash can and comprising a receptacle having a top provided with a slot adapted to be located 45 in juxtaposition to the nozzle of the vacuum cleaner, a fabric separating medium dividing said receptacle into an upper and lower compartment, said lower compartment having an inlet at one side and a discharge outlet at its bottom adapted to open into an ash can, and pivotal means for closing said outlet.

4. The combination with a motor driven portable vacuum cleaner, of a vacuum ash 55 separator adapted to rest upon an ash can and comprising a receptacle having a movable top provided with a slot adapted to be located in juxtaposition to the nozzle of the vacuum cleaner, a fabric separating medium dividing said receptacle into an upper and lower compartment, said lower compartment having an inlet at one side and a discharge outlet at its bottom adapted to open into an ash can, means for closing said outlet 60 and comprising a swinging cover, a connect-

ing link, and a rock shaft operated connection for opening and closing said cover.

5. The combination with a motor driven portable vacuum cleaner, of a vacuum ash separator adapted to rest upon an ash can 70 and comprising a receptacle having a top provided with a slot adapted to be located in juxtaposition to the nozzle of the vacuum cleaner, a fabric separating medium dividing said receptacle into an upper and lower compartment, said lower compartment having 75 an inlet at one side and a discharge outlet at its bottom adapted to open into an ash can, means for closing said outlet and comprising a swinging cover, a connecting link, a rock shaft operated connection for opening and closing said cover, and means for locking said cover closed.

6. The combination with a motor driven portable vacuum cleaner, of a vacuum ash 85 separator adapted to rest upon an ash can and comprising a receptacle having a top provided with a slot adapted to be located in juxtaposition to the nozzle of the vacuum cleaner, a fabric separating medium dividing said receptacle into an upper and lower compartment, said lower compartment having 90 an inlet at one side and a discharge outlet at its bottom adapted to open into an ash can, means for closing said outlet and comprising a swinging cover, a connecting link, a rock shaft operated connection for opening and closing said cover, and means for locking said cover closed and for limiting the movement of said rock shaft.

7. The combination with a motor driven portable vacuum cleaner, of a vacuum ash separator comprising a receptacle having a removable cover provided with a slot adapted to be located in juxtaposition with the 105 nozzle of the vacuum cleaner, a separating medium dividing said receptacle into an upper and lower compartment, said lower compartment having an inlet at one side and a discharge chute at its bottom adapted for insertion into an ash can, and manually operative means for closing said chute and comprising a rock shaft connected with said closing means and constructed to lock said closing means in its closed position.

8. The combination with a motor driven portable vacuum cleaner, of a vacuum ash separator adapted to rest upon an ash can and comprising a receptacle having a movable top provided with a slot adapted to be 120 located in juxtaposition to the nozzle of the vacuum cleaner, a separating medium dividing said receptacle into an upper and lower compartment, said lower compartment having an inlet at one side and a depending 125 discharge chute at its bottom adapted to open into said ash can, and manually operative means for closing said chute.

9. The combination with a motor driven portable vacuum cleaner, of a vacuum ash 130

- separator adapted to rest upon an ash can and comprising a receptacle having a non-fixed removable top provided with air-tight connections and having a slot of substantially the same dimensions as and adapted to be located in juxtaposition to the nozzle opening of a vacuum cleaner, a separating medium dividing said receptacle into an upper and lower compartment, said lower compartment having an inlet at one side for the attachment of a conduit and a discharge outlet at its bottom adapted to open into an ash can, and lever-controlled means for closing said outlet.
- 10 10. The combination with a motor driven portable vacuum cleaner, of a vacuum ash separator adapted to rest upon an ash can and comprising a receptacle having a non-fixed removable top provided with air-tight connections and having a slot of substantially the same dimensions as and adapted to be located in juxtaposition to the nozzle opening of a vacuum cleaner, a separating medium dividing said receptacle into an upper and lower compartment, said lower
- 5 compartment having an inlet at one side for the attachment of a conduit and a discharge outlet at its bottom adapted to open into an ash can, and means for closing said outlet, said closing means openable in a downward direction whereby the dust and dirt may fall by gravity into the ash can. 30
- 15 11. A vacuum ash separator adapted to rest upon an ash can and comprising a receptacle having an inlet at one side, a discharge outlet at its underside, a separating medium dividing said receptacle into a pair of compartments, the upper compartment having a top adapted to receive and support a portable vacuum cleaner provided with a mouth, said top having a slot adapted to communicate with said mouth, and swinging downwardly controlled closing means for said discharge outlet, and means for operating said last means. 35
- 20 25 Signed at New York, in the county of New York and State of New York, this 25th day of May, 1920. 40
